UNITED STATES PATENT OFFICE.

JACK E. TAYLOR, OF WHEELING, WEST VIRGINIA.

AIR-SHIP.

No. 849,029.

Specification of Letters Patent.

Patented April 2, 1907.

Application filed November 26, 1906. Serial No. 345,057.

To all whom it may concern:

Be it known that I, JACK E. TAYLOR, a citizen of the United States of America, and a resident of Wheeling, county of Ohio, and 5 State of West Virginia, have invented certain new and useful Improvements in Air-Ships, of which the following is a specification.

My invention relates to new and useful improvements in air-ships; and it has for its object to provide an air-ship of simple, strong, and light construction in which a great elevating and sustaining power may be developed and which may be readily steered, all the working parts being under the direct control of the operator.

A further object of the invention is to provide an air-ship which is rendered buoyant by the employment of an inclosing gas-chamber of sufficient capacity to sustain its weight, 20 thus permitting the propelling mechanism to be employed wholly for raising, lowering, and directing the course of the ship.

With these and other objects in view the invention finally consists in the particular 25 construction, arrangement, and combination of parts, which will hereinafter be fully described, reference being herein had to the accompanying drawings, forming a part of this specification, in which—

30 Figure 1 is a longitudinal horizontal section of the invention. Fig. 2 is a cross-section of the same on the line 2 2, Fig. 1. Fig. 3 is a partial vertical section through one of the upright tubes, showing a propeller mounted in said tube, gearing for said propeller, and the operating-levers and clutch. Fig. 4 is a cross-section of the rudder-supports, showing the rudder in elevation; and Fig. 5 is a detail view of the rudder-controlling 40 mechanism.

Referring to said drawings, in which like reference - numerals designate like parts throughout the several views, 1 indicates an oblong metallic shell, cylindrical in cross-section, which serves as a car for carrying the necessary driving machinery, passengers, ballast, &c. Extending longitudinally and centrally through said car 1 is a tube 2, the ends of which project beyond the ends of the 45 shell and are both open for the passage of air therethrough. Enveloping the car is an outer shell 3, similar in form to said shell 1 and braced therefrom by braces or spokes 4, spaced at suitable intervals. An annular 50 chamber 5 is thus formed between the two shells for containing gas, said chamber being

preferably of a size which will accommodate a sufficient body of gas to nearly, if not quite, sustain the weight of the machine.

Mounted in the tube 2 is a propeller-shaft 60 6, carrying a propeller 7, by means of which the machine is driven or propelled in a forward or rearward direction, according to the direction in which the propeller is driven.

Extending vertically through the two 65 shells 1 and 3 is a plurality of suitably-located tubes 8, each of which has a vertical propeller-shaft 9, centrally mounted therein, on which is mounted a propeller 10, said propellers when in operation being adapted for 70 raising and lowering the machine. Said tubes 8 are flush at their opposite ends with the outer face of the shell 3 and are firmly braced by the shells through which they extend.

75 Mounted on the floor 11, which is provided across the bottom of the car, are suitable engines 12 for driving the propellers 10, suitable gearing being provided for connecting said engines with the propeller-shafts 9, said 80 gearing preferably comprising a rotary drive-shaft 13, carried by the engine, and a suitably - supported connecting - shaft 14, said drive-shaft and connecting-shaft having intermeshing bevel-gears 15 and the propeller- 85 shaft and connecting - shaft having intermeshing bevel-gears 16. A suitable friction-clutch mechanism is provided for throwing said propeller-shaft in and out of gear with the engine. In the present instance the connecting-shaft 14 is shown in two sections 14^a and 14^b, said sections having upon their adjacent ends the clutch mechanism, which comprises a cup-socket 17, rigidly mounted on the end of the section 14^a, and a cone 18, 90 movable on the section 14^b, the cone being adapted for frictional engagement with the socket. Said cone 18 is longitudinally movable on the shaft-section 14^b, the former having a feather-key therein in engagement with 100 a longitudinal groove 19 in said shaft-section. Connected with said cone is a series of suitably-mounted connected levers leading to an operating-lever 20, mounted at a point convenient to the operator.

105 Located at suitable intervals throughout the length of the car are braces or spokes 21, having their opposite ends, respectively, mounted in the shell 1 and in the tube 2 for bracing said shell and preventing the collapse of same under the gas-pressure contained in the gas-chamber 5.

One or more engines 22 are provided for driving the propeller-shaft 6, suitable gearing being provided for the purpose.

It will be noted that the shells 1 and 3 do not embrace the tube 2 at the ends, but end at a distance from said tube, and are connected by an extension 23 of the shell 1 parallel to the tube 2, thus leaving a tubular opening 24 at each end of the machine on all sides of the tube 2. A glass or isinglass window 25 is fitted in each of these openings, which while preventing the admission of drafts of air admit of the uninterrupted passage of light to the interior of the car and admit of a certain range of vision to the car occupants.

At one or more suitable points in the floor 11 are mounted glass windows 26, through which a downward range of vision may be had by the occupants of the car, suitable openings being provided in the shells 1 and 3 below said windows, said openings being closed between the shells by plates 27.

Inclined braces 28 extend rearwardly from the ends of the shell 1 to the tube 2 for firmly holding said shell and tube in fixed relation to each other.

On the rear end of the machine is mounted a rudder, consisting of four separate fans 29 arranged in pairs, one pair standing vertical with its fans in line with each other and the other pair standing horizontal with its fans in line with each other, said rudder when viewed from either end being in the form of a cross, as shown in Fig. 4 of the drawings. The fans comprising a pair are spaced apart a short distance, admitting of the operation or manipulation of each pair without hindrance from or interference with the other. Said fans are rigidly mounted upon shafts 30, which stand at right angles to each other and have their ends journaled in the outer ends of brace-rods 31, which are rigidly mounted at their opposite ends upon the tube 2. Suitable operating-levers are provided by means of which the parts of said rudder may be manipulated.

Having thus described my invention, what I claim as new, and desire to secure by Letters Patent, is—

1. In a flying-machine, an oblong metallic shell, a tube extending longitudinally and centrally through said shell, a second shell enveloping the first-mentioned shell and spaced therefrom forming a gas-chamber between said shells, a propeller in said tube, driving means for said propeller, a plurality of tubes extended vertically through said shells, propellers in said tubes, and driving means for said propellers.

2. In a flying-machine, an oblong metallic shell, cylindrical in cross-section, a tube extending longitudinally and centrally through said shell, a propeller in said tube, an outer shell enveloping the first-mentioned shell and

braced therefrom to form a gas-chamber between the shells, a plurality of vertical tubes extended through said shells and open to the atmosphere at each end, propellers in said tubes, means for driving each of said propellers, braces holding the inner shell and the longitudinally-extending tube in fixed relation to each other, and a rudder operatively connected to said last-mentioned tube.

3. In a flying-machine, an oblong metallic shell, tubular in cross-section and open at each end, a tube open from end to end projected longitudinally and centrally through said shell, braces holding said shell and tube in fixed relation to each other, an outer shell enveloping the first-mentioned shell, a gas-chamber formed between said shells, braces holding said shells in fixed relation to each other, a plurality of tubes extended vertically through said shells, propellers in each of said tubes, motors, gearing between said motors and said propellers, clutch mechanism whereby said propellers may be thrown into and out of gear, and guiding mechanism carried by the central horizontal tube at one end thereof.

4. In a flying-machine, an oblong metallic shell, a tube extending longitudinally and centrally through said shell, a propeller in said tube, a second shell enveloping the first-mentioned shell and braced therefrom forming a gas-chamber between said shells, a plurality of vertically-disposed tubes associated with said shells and having their ends open to the atmosphere, propellers in said tubes, and means for driving said propellers.

5. In a flying-machine, an oblong metallic inner shell, an outer shell enveloping the inner shell and braced therefrom to form a gas-chamber between said shells, a tube extended longitudinally and centrally through the inner shell and having its opposite ends open and projected beyond the ends of said shells, a propeller mounted in said tube, braces between said tube and the inner shell, tubes open at each end projected vertically through said shells and firmly held thereby, and propellers in the vertical tubes.

6. In a flying-machine, inner and outer oblong metallic shells spaced apart to constitute a gas-chamber therebetween, a tube extended longitudinally and centrally through the inner shell, said shells both terminating at each end at equidistant points from said tube, tubular extensions of the inner shell connected to the ends of the outer shell and forming tubular openings about the ends of said tube, a plurality of tubes extended vertically through said shells, and propellers in each of said tubes.

7. In a flying-machine, inner and outer oblong metallic shells spaced and braced apart, a tube extended longitudinally through the inner shell, said shells terminating at their ends at points remote from said tube, the ad-

jacent ends of said shells being connected forming a closed gas-chamber between the shells and forming window-openings adjacent to the tube at each end, vertical tubes extended through said shells, propellers in each of said tubes, and driving means for said propellers.

8. In a flying-machine, inner and outer oblong metallic shells spaced and braced apart, a tube extended longitudinally through the inner shell, said shells terminating at their ends at points remote from said tube, the adjacent ends of said shells being connected forming a closed gas-chamber between the

shells and forming window-openings adjacent to the tube at each end, vertical tubes extended through said shells, propellers in each of said tubes, driving means for said propellers, brace holding the inner shell and the longitudinally-extending tube in fixed relation to each other; and a rudder operatively connected to the last-mentioned tube.

In testimony whereof I affix my signature in presence of two subscribing witnesses.

JACK E. TAYLOR.
